BOBBIN RECEPTACLE AND SUPPORT
THEREFOREdward C. Nichols, Upton, and Willard C. French,
Milton, Mass., assignors to Draper Corporation,
Hopedale, Mass., a corporation of Maine

Application April 15, 1943, Serial No. 483,094

9 Claims. (Cl. 139—255)

The present invention relates to bobbin receptacles for looms and as illustrated herein, relates more particularly to supports for such receptacles which permit the receptacle to be easily moved out of bobbin receiving position and which move the receptacle automatically into bobbin receiving position relatively to the shuttle box of the loom.

Receptacles are provided, in automatic looms, to receive and collect empty filling carriers or bobbins as they are ejected from the shuttle by an incoming filled bobbin or filling carrier. The receptacles are usually positioned below the shuttle box of the loom to receive the empty bobbins and are usually so positioned that the passageway between the looms is unobstructed. It is difficult to reach into the receptacles to remove the empty bobbins when the receptacles are in bobbin receiving position. In prior devices, provision has been made to swing or move the receptacles out of their normal positions to facilitate the removal of the empty bobbins therefrom without, however, providing any convenient means for returning the receptacles to their normal bobbin receiving positions. This is objectionable since the receptacles may remain in the passageway and interfere with other necessary operations.

An object of the present invention, accordingly, is to provide means for supporting a bobbin receptacle wherein the above mentioned difficulties will be overcome. To this end the invention contemplates a support for the receptacle wherein the bobbin receptacle automatically returns to bobbin receiving position after having been displaced therefrom either intentionally or accidentally. Thus danger of injury either to the receptacle or to the contents thereof is effectively prevented.

Another object of the invention is to improve generally upon the construction of bobbin receptacles and supports therefor.

With the above and other objects and features in view, the invention will now be described with particular reference to the accompanying drawings in which:

Fig. 1 is a view in front elevation of a portion of a loom provided with a bobbin receptacle embodying the present invention;

Fig. 2 is a view in side elevation of one of the bobbin receptacle supporting devices;

Fig. 3 is a view in section taken along the line III—III of Fig. 2;

Fig. 3A is a view in side elevation, on a some-

what reduced scale, of the construction shown in Fig. 1;

Fig. 4 is a plan view, partly in section, of the bobbin receptacle; and

Figs. 5 and 6 are views in side and front elevation respectively of the means for securing the bobbin receptacle to the side of the loom.

The invention is illustrated in the drawings as applied to an automatic loom of the filling replenishing type which is of usual and well known construction and only so much of the right hand side of the loom is shown and described as is necessary to a complete understanding of the present invention.

As shown in Figs. 1 and 2, the receptacle 10 is supported on the right hand side of the loom. Only the right hand side frame 12, the reciprocating lay 14 and the rotatable battery 16 are shown. The other parts of the loom are of usual construction and, accordingly, are not described herein.

The reciprocating lay 14 is provided with a shuttle box 18 into and out of which a shuttle (not shown) is picked by a picker stick 20. When the filling on the filling carrier in the shuttle is substantially exhausted, the parts of the mechanism are conditioned to transfer a new filling carrier from the rotatable battery 16 and into the shuttle to replace the exhausted or substantially exhausted filling carrier which is ejected through the bottom of the shuttle and into the filling carrier or bobbin receptacle 10. Thus the bobbin receptacle must be in the position shown in Fig. 3A at all times during operation of the loom.

The receptacle 10 shown in the drawings, is preferably formed of flexible textile material, such as duck, but it may be made of any other suitable flexible material if so desired. The receptacle 10 is generally substantially rectangular in cross section but it may be of any other suitable shape if desired. It is preferable to so shape the receptacle that the forward wall 19 thereof is slack so that the ejected bobbins do not strike said wall and rebound therefrom.

To this end the side walls 21 are each provided with a convex projection 23. The forward edge of each sidewall 21, therefore, is longer than the vertical length of the sidewall. The forward wall 19 has a length equal to the length of the forward edge of the sidewall 21. Thus when the forward wall 19 is stitched in place, the side walls 21 will be shorter than the forward wall which consequently will remain somewhat slack even though the receptacle 10 is substantially filled with bobbins. A receptacle so constructed will

be

contain a large number of bobbins due in part, at least, to the fact that the receptacle conforms somewhat to the bobbins and thus permits the bobbins to pack or rest more closely. The receptacle 10 is provided at its upper end with an interrupted hem 22, the hem being formed by turning the material of the bag on itself and securing the hem in position by stitching or cement. The hem 22 is interrupted at two places to permit a supporting frame to be inserted in the hem.

The supporting frame comprises a pair of rods 26 and 28, each of which is bent to fit into a portion of the hem 22 of the bag. The rod 26 is bent substantially U-shaped with one leg of the U somewhat longer than the other as shown best in Fig. 4. The rod 28 is also bent into a U-shape but the inner rear bend or corner 30 is bent at an acute angle to permit the mouth of the receptacle 10 to extend well under the bobbin guide 32 when the lay 14 is in its extreme forward position to insure that the ejected bobbins will be received in the receptacle 10. The adjoining ends of the rods 26 and 28 are secured together by supporting couplings 34 and 36.

The coupling 34 is provided with a cylindrical hole 37 in which the adjoining ends of the rods 26 and 28 are inserted after the bent rods have been threaded into the hem 22. The rods are secured in position by set screws 38 which are threaded into the coupling 34 and project into the opening or hole 37. One end, preferably the upper or forward end of the coupling 34 has formed integrally therewith a ring 40. The ring 40 receives a hook 42 formed as a part of a support 44 fixed to the loom frame 12. The support 44 comprises in addition to the hook 42, a seat 46 having an opening therethrough for receiving a bolt 48 by which the support is secured in position on the loomside. The support then is extended toward the right in the form of a partly cylindrical web 50 of which the hook 42 is a forward extension. The lower portion of the web 50 is extended to form a stop 52 against which the coupling 34 bears when the receptacle is in bobbin receiving position.

The coupling 36 which is located on the other side of the bag is the same as the coupling 34 and is provided with an opening to receive the adjoining ends of the rods 26 and 28, set screws 54 for maintaining the rods in position, and a supporting ring 56 which receives a depending hook 58 which in turn is supported for swinging movement in a bracket 60. The bracket 60 in turn is rigidly supported on the end of a stub shaft 62 which, as shown most clearly in Fig. 1, is supported by and connected by a coupling 64 to a horizontal stud 66 on which a transerrer 67 is mounted. In some cases, however, the shaft 66 may be sufficiently long and the coupling 64 and the stub shaft 62 may be eliminated and the support or bracket 60 be mounted directly on the end of the shaft 66. The bracket 60 is generally in the form of a U-shaped casting having a hole 68 in one leg to receive the shaft 62. A set screw 70 is threaded into the casting and projects into the opening 68 to lock the bracket 60 in position. The other leg of the bracket is provided with an opening 72 for receiving a bolt 74 which has a head 76 engaging a spacing collar 78 which forms a bearing for the upper closed end 80 of the hook 58. Rearward swinging movement of the hook 58 is limited by a stop 82 formed integrally with the bracket 60.

It is evident from the above that the receptacle

10 is positively supported on two sides. As shown most clearly in Figs. 2 and 4, the supporting couplings 34 and 36 are offset relatively to each other to cause the bag or receptacle 10 normally to hang in bobbin receiving position. This is accomplished by locating one of the couplings near the front of the receptacle and by so locating the support for the other coupling, that said support tends normally to urge the bag 10 into a rearward position. Thus, if the bag is displaced forwardly for any reason, the bag or receptacle will swing rearwardly when the displacing force is released.

Having thus described our invention, what we claim as new and desire to secure by Letters Patent of the United States is:

1. A loom having in combination, a loom frame, a shuttle box, filling carrier transfer mechanism cooperating with said shuttle box, a swingably mounted receptacle for receiving ejected filling carriers, and means arranged to support said receptacle on opposite sides thereof in position below said shuttle box to receive ejected filling carriers, said supporting means being constructed and arranged to permit said receptacle to return automatically to said filling carrier receiving position after having been displaced therefrom.

2. In a loom having a loom frame, a shuttle box, and filling carrier transfer mechanism cooperating with said shuttle box, the combination therewith of a receptacle for receiving ejected filling carriers, and means for supporting the receptacle in position below the shuttle box to receive the ejected filling carriers and to permit the receptacle to swing into said position, said supporting means being disposed on opposite sides of the receptacle, the means on one side being disposed further rearwardly of the receptacle than the means on the other side whereby the receptacle will swing into filling carrier receiving position.

3. In a loom having a loom frame, a shuttle box, filling carrier transfer mechanism cooperating with said shuttle box, means for supporting the transfer mechanism, a receptacle formed of flexible material for receiving ejected filling carriers, said receptacle having a loose front section against which the filling carriers are normally ejected to prevent bouncing of said filling carriers, and means arranged swingably to support said receptacle in position below said shuttle box, said supporting means being constructed and arranged normally to permit said receptacle to return to filling carrier receiving position.

4. In a loom having a loom frame, a shuttle box and filling carrier transfer mechanism cooperating with said shuttle box, the combination therewith of a receptacle for receiving ejected filling carriers, and means for supporting the receptacle in position below the shuttle box to receive the ejected filling carriers, said supporting means comprising a rigid frame for the top of the receptacle, means fixed to the frame near the forward end of said receptacle on one side, means fixed to said frame near the rearward end of said receptacle at the other side, and means supported by the loom frame cooperating with said means fixed to said frame for supporting said receptacle.

5. In a loom having a loom frame, a shuttle box, and filling carrier transfer mechanism cooperating with said shuttle box, the combination therewith of a receptacle for receiving ejected filling carriers, a frame for the upper end of said receptacle, means fixed on opposite sides of said frame, a hook-shaped member fixed to the loom

frame and cooperating with one of said last mentioned means for pivotally supporting the inner side of said receptacle, and a second hook member pivoted to the loom rearwardly of the first mentioned hook-shaped member for pivotally supporting the other side of the receptacle and permitting the receptacle to swing, generally rearwardly about the first mentioned hook-shaped member into filling carrier receiving position below said shuttle box.

6. A loom having in combination, a loom frame, a shuttle box, filling carrier transfer mechanism cooperating with said shuttle box, a receptacle for receiving ejected filling carriers and means disposed on opposite sides of said receptacle for supporting the receptacle from said loom in position below said shuttle box to receive said ejected filling carriers, said supporting means comprising cooperating means on the loom frame and on the receptacle for supporting the inner side of the receptacle, and cooperating means suspended from the loom and located rearwardly of the first mentioned supporting means for supporting the outer side of the receptacle.

7. In a loom having a loom frame, a shuttle box, filling carrier transfer mechanism cooperating with said shuttle box, and means for supporting said mechanism, the combination therewith of a pivotally mounted receptacle for receiving ejected filling carriers, a two part frame for the upper end of said receptacle, couplings for rigidly securing together adjoining ends of said frame, one of said couplings being located forwardly of the median line of said receptacle and the other of said couplings being located rearwardly thereof, a member fixed to the loom frame and on which said forwardly located coupling is supported, and a pivotally supported member for receiving and supporting the other of said couplings, said pivotally supported member being located rearwardly of said first supporting member for the purpose described.

8. In a loom having a loom frame, a shuttle box, filling carrier transfer mechanism cooperat-

ing with said shuttle box, and means for supporting said transfer mechanism, a pivotally supported receptacle for receiving ejected filling carriers, a frame for the upper end of the receptacle, said frame comprising two complementary U-shaped members inserted within a hem formed in the upper end portion of the receptacle, means for securing the adjoining ends of said frame together, means rigidly secured to the loom frame and arranged to support one side of said receptacle, and means pivotally supported on said transfer mechanism for supporting the other side of said receptacle, said pivotally supported supporting means being located rearwardly of the first mentioned receptacle supporting means to permit the receptacle to swing about said first mentioned receptacle supporting means into filling carrier receiving position below said shuttle box.

9. In a loom having a loom frame, a shuttle box, filling carrier transfer mechanism cooperating with said shuttle box, and means supporting the transfer mechanism, a pivotally supported receptacle formed of flexible material for receiving filling carriers ejected upon operation of the transfer mechanism, a frame for the upper end of said receptacle, said frame comprising two complementary U-shaped members inserted in a hem formed in the upper end portion of the receptacle, couplings for securing the adjoining ends of the frame together, ring-shaped supports formed as a part of said couplings, one of said couplings being located nearer the front of the receptacle and the other coupling being located nearer the back of said receptacle, a hook fixed to the loom frame and entering the ring near the front of the receptacle to support the inner side of said receptacle, and a second hook pivoted to said transfer mechanism supporting means and entering the other ring-shaped support to support the receptacle and to permit it to swing rearwardly into filling carrier receiving position.
